UNITED STATES PATENT OFFICE

HENRY KINNEY, OF SACRAMENTO, CALIFORNIA

PLAYER PIANO

Application filed February 13, 1928. Serial No. 254,138.

My invention relates to improvements in player pianos, and it consists in the combinations, constructions, and arrangements hereinafter described and claimed.

5 The object of this invention is to enable musical instruments such as the piano, pipe organ, reed organ, etc., to be tuned and played in absolutely perfect intonation instead of in the tempered system in general use at the 10 present time. The objection to the tempered system is that none of the intervals except the octaves are in perfect tune, therefore when several tones are used together, as they must be used in harmony, to produce a chord, 15 the result is a production of extremely disagreeable beats, waves or pulsations, the rapidity of which will depend upon the intervals used and also upon their pitch.

If we start with the lowest A on an ordinary piano which has $27\frac{3}{16}$ vibrations per second and tune a series of seven perfect octaves upward, we land on A 3480. vibrations per second, which is correct for the highest A on the piano. If we start with the 20 same A and tune a series of twelve perfect fifths upward we land on a A 3527, 31363/65536 vibrations per second which is a Pythagorean comma sharper than the A obtained by tuning octaves. This is the reason 25 why the fifths on an ordinary piano cannot be in perfect tune. Similar causes prevent tuning the other intervals perfect, but the ratios involved are different and the errors greater than with fifths. The extreme range 30 in the beat rate of some of the intervals on an ordinary piano is as follows: for fifths, from one wave in eleven seconds in the extreme bass to 9.36 beats per second in the extreme treble. For fourths, from one wave in nine 35 seconds to 14.00 beats per second. For major thirds, from 1.05 to 130.36 beats per second. For minor thirds, from 1.49 to 187.80 beats per second.

It will be seen from the preceding paragraph 40 that some means should be provided for tuning a musical instrument in perfect intonation, in order that the notes of various chords will harmonize correctly. Many authorities argue that as the fifths and 45 fourths are in fairly good tune the equally

tempered system leaves little more to be desired, but it should not be forgotten that every chord must contain a third as well as a fifth, therefore every chord is bound to contain not only the moderately slow beats 55 of the fifth, but the more rapid and disagreeable beats of the third also.

It is obvious that if two strings are set into vibration at the same time, these strings sending off sound waves that are not in an exact musical ratio to each other, or out of tune as the term is, beats will be produced. These beats are caused by the sound waves of the two strings acting first together, and then against each other, causing a periodic 65 increase and decrease in the volume of sound. When the ratio between the sound waves produced by the two strings is an exact one, neither string will gain or lose ground as compared with the other, there will be no 70 periodic change, and the combined tone of the two strings will remain constant. To determine the number of beats per second that will be produced by any two tones sounding together when their vibrations per second 75 are known, multiply the vibrations per second of the lower tone by the larger number, and the vibrations per second of the higher tone by the smaller number of their proper interval ratio; subtract the lesser product from 80 the greater and the remainder will be the number of beats per second.

For example, middle C has 258.65 vibrations per second in equal temperament. G a fifth above C has 387.54 vibrations per second. The fifth ratio is 3 to 2 therefore $(258.65 \times 3) - (387.54 \times 2) = .87$ beats per second. And again E a major third above C has 325.88 vibrations per second. The major third ratio is 5 to 4 therefore $(325.88 \times 4) - (258.65 \times 5) = 10.27$ beats per second.

When the beat rate exceeds about thirty per second, the ear cannot distinguish the separate beats, the effect being the same as another tone having as many vibrations per 95 second as there are beats per second. In many cases this third tone can be distinctly heard when as a matter of fact no such tone really does or should exist.

At this time it is well to refer to the draw- 109

ings, which show charts indicating different data and also a mechanism for permitting a musical instrument to be played that is tuned in perfect intonation.

5 Figure 1 is a schematic view of an apparatus for employing my invention;

Figure 2 is a sectional view diagrammatically shown of a portion of a player piano using my invention; and

10 Figures 3, 4, 5, and 6 are charts giving different data which will be hereinafter specifically set forth.

Before the operation of the invention can be understood it is necessary to understand 15 the system of perfect intonation with which it is proposed to be used. Figure 3 is a condensed diagram of the ratios existing between the twelve tones of any octave when tuned in perfect intonation. For brevity sake only the 20 major mode will be considered at present, but the tones obtained are absolutely correct for the minor mode also. The numbers in the horizontal row A marked Deg. represent the diatonic and chromatic degrees of the major 25 scale, No. 1 being the keynote and No. 8 the octave above the keynote. The numbers in the horizontal row B, marked Rat. are the ratios existing between the respective degrees of the major scale and the keynote 1.

30 For example, the ratio of the second degree, see reference numeral 1, is 9 to 8, which means that the second degree should make exactly 9 vibrations in the length of time required for the first degree or keynote to make 35 8. The ratio of the third degree 2 is 5 to 4, therefore the third degree of the major scale should make exactly 5 vibrations, while the keynote makes exactly four, and so on, for all of the degrees as shown.

40 The numbers 1, 15, 8, 5, etc., at the bottoms of the fractions in the B row refer to the number of vibrations given off by the keynote 1 in square 3. The lowest horizontal 45 row C in Figure 3 gives the ratios existing between the adjacent diatonic degrees of the scale. It will be observed that there is only three different ratios, namely: 9 to 8; 10 to 9; and 16 to 15. The 16 refers to the number of vibrations of note 4, see square 4, while 15 50 designates the number of vibrations of 3, square 2. These three ratios are known the world over as major tone, minor tone, and semitone. The major tone is divided into two unequal semitones, see squares 5 and 6 55 in row D, having the ratios 16 to 15, and 135 to 128. The minor tone is divided into two unequal semitones having the ratios 16 to 15 and 25 to 24, see squares 7 and 8. The semitone of course is not divided.

60 Now checking up the ratios existing between the adjacent chromatic degrees of the scale, it will be found that there is only three different ratios, namely: 16 to 15; 135 to 128; and 25 to 24. They are shown in detail in 65 the upper horizontal row D of Figure 3.

It is now best to show the number of strings necessary to provide all of the known keys with perfect intonation, and the number of vibrations given off by these strings.

Figure 4 shows the vibrations per second of the tones in the octave from A to A around middle C calculated according to the ratios given in Figure 3, taking international A at 435 vibrations per second. Thirteen different keys are shown modulating by fifths from 70 A_b to G_#, inclusive, see vertical row E. It will be observed that each of the twelve tones of the octave has four slightly different pitches or rates of vibration depending upon the key in which it is used. Therefore, to 80 play in all the keys shown in Figure 4, it will require four times twelve or forty-eight tones in each octave, which means exactly four ordinary player pianos, or their equivalent.

However, it is somewhat misleading to look 85 at it from the viewpoint of forty-eight tones to the octave. The difference in pitch of the same tone when used in different keys is so small, when compared with the difference in pitch between it and the next higher or lower 90 tone, that it is best to look at it from the viewpoint of twelve tones to the octave, each tone varying somewhat in pitch, depending upon the key in which it is used.

95 International A is shown in square 9 in Figure 4. Middle C is shown in the fifth square from the left in horizontal row F. Starting from square 10 and reading upwardly in vertical row E, it will be noted that the keynotes of the various sharp scales are 100 given. For example, horizontal row F indicates middle C, row G indicates the key of G, which has one sharp, row H indicates the key of D, which has two sharps, etc.

105 Reading down from row F we have horizontal row I, indicating the key of F, or one flat, row J indicating the key of B_b, or two flats, etc.

110 Each horizontal row has one square, see the square 9, which is provided with blackened corners. These squares give the number of vibrations necessary for the string that represents the keynote.

115 Take square 9 which shows 435 vibrations for keynote A, which also is international A. This square appears in vertical row K. Running down this row we find that international A can be used for the keys of E, B, D, and G. The key A in order to provide perfect intonation for the keys F_#, C_#, and G_# must give off 120 440 vibrations per second, see squares 10, 11, and 12.

125 Coming down to the keys of C, F, and B_b, we find 429 vibrations to be correct. The keys of E_b and A_b, take 434 vibrations for the string A. There is therefore four different strings necessary for the note A, in order to be in perfect intonation with all of the keys. Reference to the other notes shown by the names of the notes heading each vertical row 130

in Figure 4, shows that each note must have four different vibrations in order to be in perfect intonation with all of the keys. Each note on the piano must have four strings.

5 The instrument is tuned in three separate series of absolutely perfect fifths and their octaves as follows. A keynote series, a major third series, and a minor third series. The keynote series gives all the keynotes in every 10 octave also the degrees 2, 4, 5, 6½ of the major scales, see row A, Figure 3. The major third series gives the degrees 3, 6, 7 of the major scales. The minor third series gives the degrees 1½, 2½, 4½, 5½ of the major scales. 15 These three combinations take up all of the tones. The tones are most conveniently arranged in four rows, as shown in Figure 5, each row containing twelve tones to the octave. Each row indicates a separate piano or 20 a single piano having four strings to each note.

The following instructions are for tuning a battery of four pianos in perfect intonation, but are correct for a pipe organ, reed organ, 25 or other instrument by using the words row 1, row 2, etc., in place of the words piano 1, piano 2, etc.

The keynote series

30 Inasmuch as A at 435 vibrations per second is by international agreement the pitch standard of the world, we commence by tuning A, see square 13, Figure 5, on piano 3, to exactly 435 vibrations per second, then tune all A 35 tones on piano 3, in absolutely perfect octaves with this A.

Tune all E tones on piano 3 a perfect 5th above and a perfect 4th below the A tones of piano 3, and in perfect octaves with each 40 other.

Tune all B tones on piano 3 a perfect 5th above and a perfect 4th below the E tones of piano 3 and in perfect octaves with each other.

Tune all F♯ tones on piano 4 a perfect 45 fifth above and a perfect fourth below the B tones of piano 3, and in perfect octaves with each other.

Then tune tones 5, 6, 7, 8. Tune in like manner C♯, G♯, D♯, A♯ all on piano 4.

50 Tune all D tones on piano 3 a perfect fifth below, and a perfect fourth above the A tones of piano 3, and in perfect octaves with each other.

Tune all G tones on piano 2 a perfect 55 fifth below, and a perfect fourth above the D tones of piano 3, and in perfect octaves with each other.

Tones 11 to 17. Tune in like manner C and F on piano 2, also B, E, A, D, G, on 60 piano 1. This completes the keynote series.

The major third series

The requirement is that we have a series of 65 perfect fifths and their octaves, four semitones above the keynote series, and of such

pitch that they will make exactly five vibrations in the length of time required for the respective tones of the keynote series to make exactly four vibrations. If we are to tune by ear, the best way is to make the thirds 70 chord perfectly with the tones of the keynote series as follows:

Tune all F tones on piano 1 to chord perfectly in the major chord D, F, A, and in perfect octaves with each other.

Tune all C tones on piano 1 a perfect fifth above, and a perfect fourth below the F tones of piano 1 to chord perfectly in the major chord A, C, E, and in perfect octaves with each other.

Tune all G tones on piano 1 a perfect fifth above, and a perfect fourth below the C tones of piano 1 to chord perfectly in the major chord E, G, B, and in perfect octaves with each other.

Tune all D tones on piano 2 a perfect fifth above, and a perfect fourth below the G tones of piano 1 to chord perfectly in the major chord B, D, F, and in perfect octaves with each other.

Tune the tones 22 to 32. Tune in like manner A, E, B on piano 2 F♯, C♯, G♯, D♯, A♯, on piano 3 and F, C, G on piano 4. This completes the major third series.

The minor third series

The requirement is that we have a series of perfect fifths and their octaves, three semitones above the keynote series and of such pitch that they will make exactly six vibrations in the length of time required for the respective tones of the keynote series to make exactly five vibrations. They are tuned in the same manner as the major thirds forming a minor chord with the tones of the keynote series.

Tune all A tones on piano 1 to chord perfectly in the minor chord G, A, D, and in perfect octaves with each other.

Tune all D tones on piano 1 a perfect fifth below and a perfect fourth above the A tones of piano 1, and in perfect octaves with each other.

Tune all E tones on piano 1 a perfect fifth above, and a perfect fourth below the A tones of piano 1 to chord perfectly in the minor chord D, E, A, and in perfect octaves with each other.

Tune all B tones on piano 1 a perfect fifth above, and a perfect fourth below the E tones of piano 1 to chord perfectly in the minor chord A, B, E, and in perfect octaves with each other.

Tune all G tones on piano 2 a perfect fifth above, and a perfect fourth below the B tones of piano 1, to chord perfectly in the minor chord E, G, B, and in perfect octaves with each other.

Tune tones 38 to 48. Tune in like manner D, A, E, B, on piano 2, F, C, G on piano 130

3 and D, A, E, B, on piano 4. This completes the minor third series and completes the tuning of the instrument. All 48 tones in the octave have been tuned.

5 Each note of the keynote series is used in five different keys. Each tone of the minor third series is used in four different keys. Each tone of the major third series is used in three different keys.

10 The net result of the tuning is that piano one is tuned and is playable alone in the key of A $\flat$ or G $\sharp$ only. It is playable in other keys in combination with piano two. Piano two is not playable in any key alone, but only in combination with piano one or three. Piano 15 three is not playable in any key alone, but only in combination with piano two or four. Piano four is tuned exactly the same as piano one but to a somewhat sharper pitch. Piano 20 four is playable alone in the key G $\sharp$ or A $\flat$ only. It is also playable in other keys in combination with piano three. Figure 6 shows by heavy lines 14 to 18, inclusive, the grouping of the 48 tones in the four pianos.

25 Referring to Figure 4, piano one is tuned to give the tones shown in the lowest horizontal row marked L. Piano two is tuned to give the next higher tones. Piano three is tuned to give the next higher tones above piano two, and piano four is tuned to give the tones shown in the highest horizontal row marked M. The expressions used do not necessarily mean the highest or lowest in pitch but refer to their position in Figure 4.

30 35 Now when it is understood that each horizontal row of tones in Figure 4 will produce a certain scale or key, and that the four pianos combined will produce all the tones shown in Figure 4, it becomes obvious that 40 we can play in perfect intonation in at least two ways. First, we can make a separate tracker bar for each key connecting each one to the proper tones of the pianos to produce that key. Then we can play in any key desired by using the proper tracker bar. Secondly, we can make one tracker bar only and when it is desired to play in a different key disconnect such of the old tones as may be necessary, and connect the proper new tones to produce the desired scale or key. 45 50 The proposed tracker bar operates on a practical combination of the two principles.

An inspection of Figure 4 will show that when modulating upwards by fifths it is necessary to disconnect three tones in each octave for every modulation and connect three new tones. Degrees 2 and 2 $\frac{1}{2}$ of the new scale must be a Didymus comma sharper (ratio 81 to 80) and the seventh degree a diaskhisma 55 flatter than the old tones (ratio 2025 to 2048 equal to 81 to 81.92).

A Didymus comma (ratio 81 to 80) is the difference between two perfect octaves (ratio 2 to 1) plus one perfect major third (ratio 60 65 5 to 4) and four perfect fifths (ratio 3

to 2). In other words two octaves plus one major third plus one Didymus comma is exactly equal to four fifths. It is the amount that degrees 2 and 2 $\frac{1}{2}$ of the major scales must be sharpened to maintain perfect intonation when modulating upward by fifths. It is a trifle more than one-fifth of an equally tempered semitone or to be more exact, 215.

70 A skhisma (ratio 32805 to 32768) is the difference between eight fifths, and five octaves plus one major third. It is also the difference between eight-fifths plus one major third, and five octaves. In other words eight-fifths plus one skhisma is exactly equal to five octaves plus one major third. And five octaves plus one skhisma is exactly equal to eight-fifths plus one major third. It is about one-fiftieth of an equally tempered semitone or to be more exact, .0195.

75 80 85 A diaskhisma is ten skhismas. (Ratio 2025 to 2048 equal to 81 to 81.92.) It is the difference between four-fifths plus two major thirds, and three octaves. In other words, four-fifths plus two major thirds, plus one diaskhisma is exactly equal to three octaves. 90 It is the amount by which the seventh degree of the major scales must be flattened to maintain perfect intonation when modulating upward by fifths. It is a trifle less than one-fifth of an equally tempered semitone, or 95 to be more exact, .1955.

95 100 105 A Pythagorean comma is equal to one Didymus comma plus one skhisma. (Ratio 531441 to 524288.) It is the difference between seven octaves and twelve-fifths. In other words, seven octaves plus one Pythagorean comma is exactly equal to twelve-fifths. It is less than one-fourth of an equally tempered semitone, or to be more exact, 2346.

110 115 120 The tracker bar under consideration is arranged and connected up in such a way that these operations can be readily performed, see Figures 1 and 2. It consists essentially of a face plate 19 having thirteen rows of holes 20, there being one row of holes for each key in which it is desired to play. Some four rows of tracker tubes 21 to 24, inclusive, are connected to this face plate in such a way that each row of holes in the face plate will be connected to the proper tones of the pianos, or single piano having four strings to each note, to produce its intended key. Each tone of the keynote series is connected to five openings in the face plate, each tone of the minor third series to four and each tone of the major third series to three openings in the face plate. Of course, at the top or bottom of the face plate any tone may be connected to not more than one opening, but if the face plate were extended farther, each tone would have the number stated. The exact number in each individual case can be seen in Figure 1 and also in Figure 4.

125 130 A tuning roll 25 made of special tough

paper or other suitable material is placed over the entire surface of the face plate or tracker bar 19. This tuning roll is similar to a music roll, only much shorter. It has one row of holes 26, similar in size and shape to a row of holes in the face plate, and it is adapted to be moved so as to bring the row of holes in the tuning roll into alignment with any desired row of holes, in the face plate, at the same time keeping all the other rows closed 10 air tight. Then a standard music roll 27 is used with the exposed row of holes exactly the same as if using an ordinary tracker bar; and the music produced will be in perfect intonation and free from the disagreeable beats 15 of the equally tempered system.

It is obvious that as several adjacent holes in the face plate discharge into the same tracker tube, they could be connected together forming one larger opening in the form of a slot. This would probably make it easier and cheaper to construct and at the same time be just as efficient. The face plate would then have much the same appearance 25 as the right hand portion X of Figure 1.

Figure 2 shows a cross sectional diagrammatic view taken through international A. The figure is correct for any A, but of course the vibrations per second will be different in 30 each octave. The two spools or rollers 28 and 29 shown carrying the tuning roll are rotatable, in order to accurately align the openings 26 in the tuning roll 25 with the openings 20 in the tracker bar 19. The lower 35 spool 29 is equipped with a spring 30 similar to those used in window shade rollers, and maintains a constant pull or tension on the tuning roll 25 at all times. A shaft 31, carrying the spool 29 is rotated by the upper 40 spool 28. The upper tuning roller 28 has a small hand wheel 32 rigidly attached to its right hand end, and its left hand end is fitted with an ordinary pawl 33 and ratchet 34. This ratchet and the diameter of the tuning 45 roller is carefully designed so that one notch on the ratchet will exactly equal the movement of the openings in the tuning roll from one to the next adjacent row of openings in the tracker bar. When it is desired to modulate into a higher key, the player merely turns the roller forward the required amount. When it is desired to modulate to a lower 50 key, the pawl is released with the left hand, the roller is allowed to rotate backward the required amount, and the pawl is allowed to 55 reengage the ratchet.

The chromatic scale will require twelve tones to the octave to play in one key, and for each additional key three new tones in 60 each octave when modulating by fifths. The diatonic scale, such as is used on the German style accordions, harmonicas, etc., will require seven tones to the octave to play in one key, and for each additional key two tones 65 in each octave when modulating by fifths.

The reason for starting with A_b and modulating to G_#, as shown in Figure 4, is to bring the natural keys that are used the most into the center of the combination and create a well balanced appearance. It does not make any real difference on which key we start 70 except that the instrument will have to be tuned to correspond.

I claim:

1. A player piano having a plurality of 75 strings for each note, a tracker tube for each string, means for closing all but the desired tracker tubes, and a perforated strip cooperating with said means for last named tubes.

2. A player piano having four strings for 80 each note, a tracker tube for each string, means for uncovering a different combination of tracker tubes for each key played, and a perforated strip cooperating with said means for closing and opening said group of tubes 85 in a predetermined manner.

3. A musical instrument having four sound producing elements of slightly varying vibration periods for each note so as to allow the player to select the elements that will 90 harmonize best with another note.

4. A musical instrument having four strings for each note, the strings being tuned in a predetermined manner for providing a major third series and a minor third series, each series consisting of perfect fifths. 95

HENRY KINNEY.
